MAILBOX SUPPORT OR THE LIKE

Robert W. Moore, Attleboro, Mass.

Application October 12, 1955, Serial No. 38,333

Term of patent 14 years

(Cl. D74—9)

Fig. 1.

Fig. 2.

Fig. 3.

Fig. 1 is a side perspective view of a mail box support showing my new design;

Fig. 2 is a side elevational view; and

Fig. 3 is a front elevational view with parts thereof being shown broken away for convenience of illustration.

The broken line illustration of a mail box shown in Fig. 1 is merely for purposes of illustration.

I claim:

The ornamental design for a mailbox support or the like, shown and described.
